UNITED STATES PATENT OFFICE.

EDMUND SPRUNG, OF DETROIT, MICHIGAN, ASSIGNOR OF ONE-HALF TO WILLIAM D. HEALY, OF DETROIT, MICHIGAN.

CARBURETER.

1,073,179.

Specification of Letters Patent. Patented Sept. 16, 1913.

Application filed March 24, 1913. Serial No. 756,380.

To all whom it may concern:

Be it known that I, EDMUND SPRUNG, a citizen of the United States of America, residing at Detroit, in the county of Wayne and State of Michigan, have invented certain new and useful Improvements in Carbureters, of which the following is a specification, reference being had therein to the accompanying drawings.

10 This invention relates to improvements in carbureters and its object is to provide a construction in which the fuel will be supplied in proportion to the speed of the engine, a series of nozzles being so arranged 15 and controlled that as the throttle is opened and the speed of the engine increases the nozzles will be successively uncovered in proportion to the movement of the throttle.

It is also an object of the invention to 20 provide a simple and efficient means for controlling the air supply, which means are arranged to be automatically operated by the suction of the engine.

A further object of the invention is to 25 provide a simple and compact construction having certain other new and useful features of construction and arrangement of parts, all as hereinafter more fully described, reference being had to the accompanying drawings.

30 To these ends the invention consists in the matters hereinafter more fully described and particularly pointed out in the appended claims.

35 Referring to the accompanying drawings, Figure 1 is a plan view of a device embodying the invention; Fig. 2 a side elevation of the same; Fig. 3 is a vertical section on the line III—III of Fig. 1; Fig. 4 is a transverse vertical section on the line IV—IV of Fig. 1, and Fig. 5 is a sectional detail on the line V—V of Fig. 2.

In the drawing, 1 indicates a casing forming a suitable float chamber for a float 2 45 which is guided in its vertical movement by a stem 3 at its upper end extending upward through a guide bearing in a cover 4 for the chamber. At its lower end the float is guided by means of a stem 5 having a valve 50 member 6 on its lower end to engage a seat in the bottom of the casing to control the inflow of gasoline from a supply coupling 7 attached to the bottom of the casing.

A hollow extension 8 extends laterally 55 from one side of the float chamber 1 and

leading into the bottom of this hollow extension is a draw-off cock 9 for drawing off the contents of the float chamber.

A tubular member or barrel 10 is seated upon the upper side of the extension 8 and extends horizontally across the extension. Bolts 11 secure it in place thereon and an opening is provided in its lower side opposite a series of vertical bores 12 into which a series of jet pipes or nozzles 13 are secured 65 and extend upwardly across the barrel. Fuel is admitted to the nozzles by means of needle valves 14 controlling openings leading from the interior of the extension 8 into the bottoms of the bores 12. The stems of 70 the needle valves 14 extend outward through stuffing boxes 15 and may be engaged at their outer ends and turned to accurately adjust them toward or from their seats and regulate the supply of fuel to each of the 75 nozzles. The barrel 10 is formed with an upwardly projecting tubular extension 16 forming an outlet passage directly opposite the upper ends of the jet nozzles 13. This tubular extension is provided with a lateral 80 flange for attaching the carbureter to the intake manifold of an internal combustion engine, and in this outlet passage 16 is a throttle valve 17 of the usual construction mounted upon a transverse stem 18 extending outwardly through one wall of the passage. Secured upon the outer end of the stem is an arm 19 for turning the valve, this arm being actuated in any suitable manner, not shown. Fitting within the tubular casing 90 or barrel 10 is a tubular shutter 20 reciprocable within the barrel across the inner end of the discharge or outlet passage 16. This member 20 is open at one end and closed at its opposite end, a stem or rod 21 being secured to the closed end of the shutter and extending outward through a bearing in the end of the barrel. The shutter is provided with a slot 22 in its lower side through which the nozzles 13 extend and thus the shutter 100 may be moved longitudinally in the barrel to bring its upper closed side across the discharge passage 16 and over the upper ends of the nozzles 13 which ends extend to within a very short distance of the upper closed 105 side of the shutter, the shutter is also formed with a notch 23 in one end at its upper side so that when the shutter is moved inward to the limit of its movement the notch will form a small opening through which the in-

terior of the barrel will communicate with the outlet passage and this notch is close to the upper end of the end nozzle of the row of nozzles.

- 5 An arm 24 is secured to and extends laterally from the outer end of the rod 21 by means of which the shutter is moved and pivotally connected to this arm is a connecting rod or link 25 which is pivotally attached at its opposite end to the arm 19 on the stem of the throttle valve 17. It will thus be seen that when the throttle valve is operated by turning the arm 19, the shutter 20 will also be moved, the connection being 10 such that as the throttle valve is opened the shutter will be proportionately withdrawn from over the upper ends of the jet nozzles, uncovering one or more of these nozzles according to the amount which the throttle is 15 opened and the consequent increase of speed of the engine. A stop screw 43 is carried by the arm 24 to engage the end of the casing 10 and limit the movement of the shutter across the outlet passage.
- 20 25 Means for controlling the admission of air to the open end of the barrel comprises a suitable tubular air inlet casing 26, one end of which is formed to fit within a seat provided therefor in the end of the barrel 30 and adapted to be secured in place therein by means of a clamping screw 27. At its outer end the casing is formed with an enlarged lateral extension 28 which is provided with a cap 29 having an axial air inlet opening and formed with a spider 30 extending across the opening to provide a bearing for an adjustable valve stem or guide rod 31 having screw-threaded engagement with the bearing and locked in position in which it 35 is adjusted by means of a winged nut 32. Sleeved upon the stem 31 to slide freely thereon and cover the inlet opening in the cap 29, is a disk valve 33 and to normally hold this valve to its seat over the air inlet 40 opening, a coiled spring 34 is sleeved upon the stem between the valve and a head 35 on the lower end of the stem. This spring 34 is comparatively weak and the valve will therefore open a short distance when the 45 engine is running at low speeds and the suction is correspondingly weak. To offer a further and higher resistance to the opening of the valve 33 when the speed of the engine is increased, a second coil spring 36 is 50 sleeved upon the stem but this spring is of lesser length than the spring 34 and does not seat upon the head 35 when the valve is closed but only engages said head and comes into action to resist the opening of the 55 valve when the spring 34 has yielded and permitted the valve to open a short distance against the resistance of said spring 34 only. The air inlet casing is also formed with a lateral extension 37 directly opposite 60 the extension 28. This extension forms the

main air inlet for the carburetor and its outer end is formed so that a pipe or other conductor (not shown) may be attached thereto to conduct heated air from any convenient source to the carburetor.

70 Within the main inlet 37 is a valve 38 adapted to be turned by means of an arm 39 on the outer end of its shaft to close the main air passage. A second arm 40 is secured to the shaft of the valve 38 and extends laterally in such position that when the valve is turned said arm will be swung into engagement with the lower end of a push rod 41 which is mounted in a suitable bearing or opening in the casing and extends 80 upward therethrough with its upper end directly below the valve 33. When the valve 38 is turned by the rod 42 or other suitable means, to close the main air inlet and thus choke the carburetor for starting purposes, the arm 40 will lift the push rod 41 into engagement with the valve 33 and hold said valve closed so that it will not be opened by the suction of the engine. The full force of the suction will therefore be 90 exerted to draw fuel through the jet nozzles and a very strong charge will thus be supplied for priming the engine.

95 In this construction the inrushing air is directed upward around and over the upper end of the nozzle or nozzles which are uncovered by the shutter and thus the mixture may be accurately regulated for the different engine speeds as the needle valves for the different jet nozzles may be differently adjusted to give the desired supply of fuel for the particular speed which will be reached when the throttle valve is opened a certain distance and a certain nozzle is uncovered by the corresponding movement of the 105 shutter.

110 The particular arrangement of the air inlet control gives an accurate automatic regulation of air supply which may be entirely cut off for starting the engine if so desired.

Having thus fully described my invention, what I claim is:—

1. In a carburetor the combination of a horizontally disposed tubular casing open at one end and having a discharge passage leading laterally therefrom intermediate its ends, a series of jet nozzles arranged in a row longitudinally of the tubular casing and extending across the same with their discharge ends opposite the discharge passage, a tubular shutter fitting within the casing to slide therein and provided with an open end and a slot in one side to receive the nozzles, the opposite side of the shutter being closed to extend over the discharge 115 ends of the nozzles and across the outlet passage of the casing, a rod having a bearing in the end of the casing and secured to the closed end of the shutter, a throttle valve 120 in the outlet passage of the casing, an arm 125

for operating the throttle valve and a rod connecting the arm and the outer end of the rod attached to the shutter for simultaneously operating the throttle valve and shutter.

2. In a carbureter, the combination of a casing forming a float chamber and having a hollow lateral extension formed with a series of vertical bores opening through the upper side thereof, a tubular casing secured upon said extension in horizontal position and formed with an outlet passage at one side and a slot in its lower side, said casing being open at one end and closed at its opposite end, a series of jet nozzles secured in the bores of the lateral extension of the float chamber casing and extending upward through the opening in the bottom of the tubular casing with their discharge ends adjacent to the upper side of the casing and opposite the outlet passage, a tubular shutter slidable within the tubular casing and formed with an open end and a slot in one side to receive the row of nozzles, the opposite side of said shutter being closed and provided with a notch in the open end of the shutter, said closed side of the shutter being adapted to project across the outlet passage of the casing over the open discharge ends of the nozzles when the shutter is moved in the casing, a rod secured to the closed end of the shutter and having a bearing in the ends of the casing, a throttle valve turnable within the outlet passage, an arm for operating the throttle valve, a rod connecting said arm and the outer end of the rod which is secured to the shutter, and a tubular air inlet casing forming an extension of the tubular casing, and provided with a main and an auxiliary air inlet.
3. In a carbureter, the combination of a tubular casing open at one end and closed at its opposite end, formed with an outlet passage intermediate its ends, a series of jet nozzles extending across the casing and arranged in a longitudinal row with their discharge ends opposite the outlet passage of the casing, a shutter slidable longitudi-

nally within the tubular casing across the outlet passage and over the ends of the nozzles, means for moving the shutter, an air inlet casing forming a continuation of the tubular casing and detachably attached thereto, said casing being formed with a main air inlet at one side and an auxiliary air inlet at its opposite side, a valve to control the auxiliary air inlet adapted to be opened by suction through the carbureter and a spring within the casing for yieldingly holding the valve closed.

4. In a carbureter, the combination of a casing having an outlet passage and opened at one end, means for supplying fuel to the interior of said casing, an air inlet casing detachably secured to the open end of said casing and formed with a main air inlet opening at one side and an auxiliary air inlet opening at the opposite side, a valve for closing each of the air inlet openings and means for actuating one of the valves to closed position and holding the other of said valves in closed position.

5. In a carbureter, the combination of a main casing having an open end and a lateral discharge passage, means for supplying fuel to said casing, a tubular air inlet casing forming a continuation of the main casing and adjustably secured thereto, said air inlet casing being formed with a main air inlet opening at one side and an auxiliary air inlet opening at the opposite side, a valve for closing the auxiliary opening, a spring to normally hold said valve closed, a valve to close the main air inlet opening, means for operating said valve in the main air inlet opening, and means operated by the actuation of said valve for holding the valve controlling the auxiliary air inlet in closed position.

In testimony whereof I affix my signature in presence of two witnesses.

EDMUND SPRUNG.
